United States Patent Office.

VIRGIL W. BLANCHARD, OF BRIDPORT, ASSIGNOR TO HIMSELF AND A. J. SEVERANCE, OF MIDDLEBURY, VERMONT.

Letters Patent No. 99,139, dated January 25, 1870.

IMPROVED STONE-CHANNELLING MACHINE.

The Schedule referred to in these Letters Patent and making part of the same

To all whom it may concern:

Be it known that I, VIRGIL W. BLANCHARD, of Bridport, in the county of Addison, and State of Vermont, have invented certain new and useful Improvements in Channelling and Dressing-Machines; and I do hereby declare that the following is a full, clear, and exact description thereof, reference being had to the accompanying drawings, and to the letters of reference marked thereon, which form a part of this specification, in which—

Figure 1 represents a side elevation of my machine.

Figure 2 is a plan view of the same.

In the drawings annexed—

A represents a platform, with the tongues on its upper surface extending lengthwise of said platform.

B designates a truck, the wheels of which are grooved, to receive the tongues *s s*, thus enabling the truck to move with the ease required.

C is a sliding bar, held in position by the cleats *d d*, the said cleats being secured to the outer edge of truck B.

To the inner side of bar C the rack-bar *e* is fastened, the office of which will be hereinafter described.

g, in fig. 2, represents a spindle, to one end of which is adjusted a spur-wheel, *h*, and to the other end is secured the pinion *t*, which gears into the rack-bar *e*.

n represents a worm-spindle, placed directly beneath spur-wheel *h*, and gearing into said wheel.

The spindle *n* is operated by a crank, *m*.

H is a cylindrical shaft, running parallel with sliding bar C, and confined to the side of the truck by cleats *d d*.

Near the upper end of shaft H, the spur-wheel G is adjusted as follows:

A groove is cut in shaft H, and a corresponding slot cut in the edge of the hole through which the shaft passes. A wedge being inserted in the slot and groove, the shaft may be raised or lowered, without altering the position of wheel G, which will rest on the surface of the truck-frame.

L represents a spindle, which passes vertically through the top of the truck-frame B, and is supplied with a spur-wheel, *J*, which gears into G.

On the upper end of spindle L is a pulley, E, by which the motion is communicated to the channelling-apparatus.

K represents a cylindrical shaft, passing vertically through the truck-frame B, and having near its lower end a spur-wheel, *o*, which gears into the rack-bar P on platform A.

On or near the upper end of shaft K is adjusted the loose pinion V, which gears into wheel J.

a designates a clutch-lever, which embraces the feathered pulley *u* on shaft K, and directly above pinion V.

The under side of pulley *u* is furnished with a tooth, which is designed to enter a slot in pinion V.

When it is desired to arrest the progressive motion of the tool, by means of the clutch-lever *a*, the said lever will be lowered, so as to relieve the tooth from the slot in V.

F represents a rectangular lever, having its fulcrum at the point *z*.

The upper end of lever F is connected with pulley E by means of a rod, X. It will be seen that the rod X, in place of being attached to pulley E at its centre, embraces a bolt near the circumference of said pulley, and will give, in its revolutions, a reciprocating motion to lever F.

The horizontal arm of lever F is connected with the piston-rod of pump W, and forces the water through the pipe T, for the purpose hereinafter described.

Y designates a second pipe, through which the pump W is supplied with water.

It will be remarked that the shaft H and sliding bar C are connected near their lower ends, by means of a metal box, R, which is made to embrace both the shaft and the bar, the said band being made water-tight at bottom.

To the lower end of shaft H is fastened, in any suitable manner, the cutting-apparatus M, in which diamonds, or other material of requisite properties may be used.

In order to soften the rock to be acted on, and also, to remove the dust produced by the channelling-process, a constant flow of water will proceed from pump W, through pipe T, into box R, and then into a cavity in M, from which it will escape through small holes *i*, into the channel formed in the rock, and serve the two-fold purpose of keeping the cutting-apparatus cool and of removing the detritus.

In the operation of my machine, the track or platform A, which supports the cutting-apparatus, is to be placed above the stone that is to be channelled.

Motion will be given to the feed-shaft K, by means of a band from the motive-power to the pulley E on shaft L.

The wheel J, being on shaft L, will communicate motion to shaft H, to the bottom of which the channelling-tool M is attached.

As the spur-wheel O is on shaft K, the said wheel will communicate with rack-bar P, and move the truck to the end of said bar, while the cutting-tool will, by the rapid rotary motion given it by means of the spur-wheel G, perform its office of channelling the rock.

When the end of the channel is reached, the action of the shaft H, with its tool M, will be arrested by means of clutch-lever *a*, which, by being lowered at its outer end, will release the tooth on pulley *u* from the slot in pinion V, when the said pinion will revolve

loosely around shaft K, and fail to communicate motion to the connecting-wheel J and wheel G, on shaft H.

The next step will be to lower the shaft H, with cutting-tool annexed, for the purpose of deepening the channel. This can be done by operating the crank m, at the end of worm-spindle n, which, being geared into wheel h on shaft g, will operate pinion t. The said pinion gearing in the rack-bar e, will operate sliding-bar C, and with it shaft H.

When the shaft is lowered sufficiently, the pinion V will again be made to perform its office, by raising the end of lever a to its original position, and thus render pinion V rigid with the shaft K.

By reversing the motion of the motive-power, the truck B will be carried back to the point from which it started, and the channel in the rock deepened, by the retrograde action of the tool M. This alternate movement of the truck can be observed until the channel is cut to the required depth.

When necessary, two channelling-machines may be used, one on each edge of platform A, with the motive-power placed between.

Having thus described my machine, What I claim, and desire to secure by Letters Patent, is—

1. A stone-channelling tool, which has a continuous motion, both of rotation on its axis and of progression in the line of the channel, substantially as and for the purpose set forth.

2. The sliding bar C, provided with box R, in combination with the revolving channelling-tool M, operating as described.

3. The sliding bar C, provided with rack-bar e, in combination with pinion t, worm-spindle n, spur-wheel h, and crank m, all arranged to operate substantially as described.

In testimony that I claim the foregoing as my own, I affix my signature, in presence of two witnesses.

VIRGIL W. BLANCHARD.
